W. PRELLWITZ

STEEL RETAINER

Filed Nov. 12, 1926

UNITED STATES PATENT OFFICE.

WILLIAM PRELLWITZ, OF EASTON, PENNSYLVANIA, ASSIGNOR TO INGERSOLL-RAND COMPANY, OF JERSEY CITY, NEW JERSEY, A CORPORATION OF NEW JERSEY.

STEEL RETAINER.

Application filed November 12, 1926. Serial No. 147,951.

This invention relates to rock drills, but more particularly to a steel retainer for fluid actuated rock drills of the hammer type in which the working implement is provided 5 with a collar or other equivalent means for limiting the distance which the drill steel may extend into the percussive tool.

The objects of the invention are to insure retention of the working implement in the 10 rock drill and to construct a rugged retaining device for rock drill steels which may be cheaply manufactured and which comprises only a few simple parts.

Other objects will appear hereinafter.

15 The invention is shown in one of its preferred forms in the accompanying drawings, in which

Figure 1 is a side view in elevation of a front end of a rock drill having the invention applied thereto,

20 Figure 2 is a front view in elevation of a portion of a rock drill showing the manner in which the retainer is held against oscillation as well as against contact with 25 the front head of the drill, and

Figure 3 is a sectional view taken through Figure 1 on the line 3—3 looking in the direction of the arrows.

25 Referring more particularly to the drawings, A represents the front end of a cylinder and B a front head, in this instance held in spaced relation with respect to the cylinder A by a front cylinder washer C. Lugs D are carried by the front head B to receive spring pressed side bolts E whereby the front head and other casing parts, such as the cylinder A and the front cylinder washer C may be clamped securely in assembled position.

30 In the front end of the front head B is formed a recess F into which extends loosely a collar G of a drill steel H. A shank J of the drill steel H extends rearwardly of the collar G into the front head to receive the 35 blows of the hammer piston (not shown).

In the present instance the front head B is provided with oppositely disposed trunnions K preferably offset from the longitudinal axis of the front head. The trunnions K in this instance resemble truncated cones and are so arranged on the front head that the largest diameter is at the outer free ends of the trunnions. In this way, a ta-

pered or inclined perimetric surface is provided for a purpose to be described more 55 fully hereinafter.

Means are provided for preventing ejection of the drill steel H from the front head B. To this end a yoke L is arranged to partly encircle the drill steel H forwardly 60 of the collar G and has rearwardly extending side arms O carrying at their rearward or free ends closed loops P. The front ends Q of the loops P are so shaped as to conform to the shape of the trunnions K and the rearward ends R of the loops may be formed to any convenient curve.

The side arms O and the loops P are formed of a single piece of wire of any suitable cross sectional area necessary to withstand the severe usage to which devices of this type are subjected. Preferably, the free ends of the side arms are slightly contracted toward each other so that when the yoke is in position on the front head a slight spring 75 effect will be obtained tending to press the side arms against the front head.

The shock absorbing or cushioning means in this instance comprises coil springs S interposed between the rearward surfaces of 80 the trunnions K and the rearward ends of the loops P. These springs S are preferably of a suitable length to enable them to exert a constant pressure in a rearwardly or upwardly direction for holding the front ends 85 Q of the loops P firmly against the trunnions K.

To the end that the springs S may be conveniently held in operative position in the loops P, spring seats T are provided for the rearward ends of the springs and are grooved as at U to engage the inner surface of the rearward ends R of the loops P for preventing relative transverse movement between the spring seats T and the loops P. 95 Preferably projections V are formed on the spring seats T to extend into the rearward ends of the springs.

Suitable supports are provided for the front ends of the springs S in the form 100 of bearings W having reduced extensions or tips X which extend into the front ends of the springs. The bearings W are recessed as at Y to conform to the conical surfaces of the trunnions K for preventing outward movement of the bearings on the 105

trunnions, that is, movement of the bearings in the direction of the outer enlarged end of the trunnions.

In order that the yoke L may be normally held in retaining position, lugs Z are formed on opposite sides of the front head B and are provided with grooves b to receive the side arms O. The said grooves in this instance are rather shallow to enable the side arms O to be readily rocked into and out of engagement therewith. The lugs Z are preferably formed rearwardly of the trunnions K and in addition to their functions of preventing free oscillation of the yoke L on the trunnions K also hold the side arms O free of the front head B throughout their lengths. In this way the yoke will be protected against breakage which frequently happens due to the impact of the side arms against the front head whenever the drill steel strikes the yoke.

In assembling the device on the rock drill, the side arms O may be spread to enable the loops P to be placed about the trunnions K. Thereafter the bearings W may be placed on the trunnions and the springs S and spring seats may then be placed in their proper relative positions. The springs S may then be compressed sufficiently to enable the spring seats T to be pressed in engagement with the rearward ends R of the loops P.

During the operation of the device whenever it is desired to remove the drill steel from the front head B, the yoke L may be rocked out of the path of the collar G of the drill steel, thus providing a free path for the removal of said drill steel. After another drill steel has again been inserted in the front head, the yoke may be rocked to its retaining position. In this position the side arms O will engage the grooves b and, due to the inherent resiliency of the yoke, the side arms will be held firmly in engagement with said grooves. However, when the yoke is rocked about the trunnions the side arms will spread readily to enable them to pass over the ends of the lugs Z.

I claim:

1. A drill steel retainer comprising a front head having trunnions, said trunnions having inwardly tapering bearing surfaces, bearings on said trunnions, said bearings having inwardly tapering bearing surfaces 55 cooperating with said inwardly tapering bearing surfaces on said trunnions and having spring centering tips, springs centered on said bearings, spring seats having centering tips carried by said springs, a retainer in the form of looped resilient member embracing the drill steel, the free ends of the arms of said retainer being bent to form elongated loops embracing the trunnions and spring seats at each side of the 65 front head, whereby the bearings on said trunnions tend to press inwardly towards the sides of the front head while the arms of the retainer swing free and clear of the front end of the front head, and retaining 70 lugs at each side of the front head cooperating with the retainer rearwardly of the trunnions.

2. A drill steel retainer comprising a front head having trunnions, said trunnions having inwardly tapering bearing surfaces, bearings on said trunnions, said bearing having inwardly tapering bearing surfaces 75 cooperating with said inwardly tapering bearing surfaces on said trunnions and having spring centering tips, helical springs centered on said centering tips, spring seats having centering tips and grooves at the opposite ends, carried by said springs, a retainer in the form of a looped resilient 80 member having a U shaped portion at its forward end embracing the drill steel, the free ends of the arms of said retainer being bent to form elongated loops passing around the trunnions and over the spring 85 seats at each side of the front head and lugs at each side of the front head having sloping sides and a groove at the apex to cooperate with said retainer to hold the retainer in a normally retaining position. 90 95

In testimony whereof I have signed this specification.

WILLIAM PRELLWITZ.
